SPARK PLUG

Eugène Excoffier, Chemin du Moulin-Sannois,
FranceApplication August 26, 1931, Serial No. 558,392
In France August 22, 1930

2 Claims. (Cl. 122—169)

This invention has reference to improvements in sparking plugs of the kind having a metal sleeve between a casing or body and an insulator surrounding a centrally arranged electrode.

- 5 In the known sparking plugs of the kind referred to the metal sleeves tightly fit the parts between which they are interposed and either have to be accurately made in order to ensure a close fluid-tight fit or have to be of a metal 10 sufficiently soft to enable the sleeve to be distorted so as to conform with small irregularities in the shapes of the casing and insulator. Other known plugs not employing sleeves have, chiefly for the purpose of obtaining fluid-tightness, had 15 their casings cast directly on insulators surrounding central electrodes. This has necessitated the use of an insulator having special heat resisting qualities and, even so, it frequently happened, by reason of play as a result of unequal contractions 20 in cooling, that cohesion between the sleeve and insulator and the molecules comprising the insulator was detrimentally affected, the plug thus losing its fluid-tightness and having its useful life considerably shortened.
- 25 The primary object of the present invention is to provide a sparking plug in which a high degree of fluid-tightness is ensured without it being necessary specially to construct the metal sleeve or to employ an insulator resistant to high temperatures and molten metal; and according to 30 the present invention a sparking plug having an insulator surrounded by a metal sleeve is characterized in that the casing or body of the plug is cast on the sleeve with the result that the sleeve 35 and casing become fluid-tightly united but molten metal is prevented from directly touching the insulator. The fact that the casing is cast on the sleeve is necessary only to ensure close fit between the insulator and bore of the sleeve, fluid-tightness between the sleeve and the casing.

The insulator used in the present invention is preferably of the kind comprising a number of washers arranged face to face around the central electrode or comprising a number of turns of mica plates around the said electrode.

40 The use of the sleeve also permits of obtaining cast plugs with a hollow electrode or with air circulating and still fluid-tight plugs which are capable of being taken to pieces.

45 An example of the invention is illustrated in the accompanying drawing which is a side view of one of my plugs chiefly in vertical section.

In this example the plug has a central rod 1 which is screw-threaded at its upper end and 50 is provided with a head 5 at its lower end and a

central electrode bent at 2 to form an electrode proper. That part of the rod between the head 5 at its lower end and the screw-threaded portion is closely surrounded by a cylinder 3 comprising a number of turns of mica and the mica cylinder is surrounded by a number of mica washers 3'.

55 The body comprising parts 1, 2, 3 and 3' is inserted in a sleeve 4 and, in accordance with the invention, this sleeve has cast on it an extended aluminium bronze or aluminium brass casing 6 of known form 7, for the retention of a grounded electrode 8. The electrode 8 comprising a pin which is preferably placed in the mould at the time of casting the casing. Washers 3' tightly 60 fit the bore of sleeve 4 and when the casing 6 contracts owing to its cooling, sleeve 4 is contracted and tightly grips the peripheries of the washers.

70 The mica washers above the upper end of sleeve 4 preferably have imparted to them in a lathe a slightly conical shape as indicated by 12.

75 It will be understood that mica cylinder 3 may be dispensed with and the mica washers 3' be suitably fashioned to take the place of said cylinder.

80 The mica bodies 3 and 3' are clamped between the enlargement 5 and lower end of the screw-thread by means of nut 15 which comprises a counter nut to a thumb or terminal nut 16.

85 For the purpose of preventing the central electrode from unintentionally falling or being driven through the casing 6 the inner wall of the casing extension has an enlargement or boss 7 which ordinarily lies in the path of the head 5 when the electrode 1 is moved downwardly, but in order to permit the said electrode to be intentionally removed for cleaning and replacement purposes the enlargement 5 is grooved at 19 and, by turning this groove into register with boss 7, electrode 1 90 may be withdrawn.

95 Having now particularly described and ascertained the nature of my said invention and in what manner the same is to be performed I declare that what I claim is:

1. A spark plug comprising a central, insulated electrode, consisting of a mica cylinder, a series of mica disks embracing the cylinder, a metal sleeve surrounding the mica insulation and a plug body in cast welded connection with the sleeve.

100 2. A spark plug as claimed in claim 1, in which the lower part of the casing is formed with a projection to prevent accidental removal of the central electrode.
